ABSTRACT OF THE DISCLOSURE

Apparatus to narrow the energy distribution of an electron beam wherein an electron reflector receives at the input thereof an electron beam. The electrons of the beam are forced to geometrically undergo successive collisions with the reflecting surface of the reflector. The output electron beam from the reflector has a substantially narrower energy distribution than the input electron beam.

BACKGROUND OF THE INVENTION

This invention relates to a method and apparatus for controlling an electron beam, and more particularly, to a method and apparatus for using the energy (velocity) dependence of the electron reflection coefficient to produce an electron beam having a narrower energy (velocity) distribution than the original source beam by geometrically forcing the electrons to undergo successive collisions with a reflecting surface.

Many devices such as electron microscopes, radar display tubes, television picture tubes, electron diffraction instruments, etc., are limited by the energy spread of the electron beams used. In the prior art, there exists the technically difficult problem of producing low-energy electron beams with narrow energy (velocity) spreads and in the past complex apparatus has been necessary to solve the problem.

SUMMARY OF THE INVENTION

The reflection coefficient R of a given surface for low-energy electrons (say for $E \leq 3-5$ ev.) is known to depend on the energy E with which the electrons hit the surface. Also, in this same energy range, the reflected electrons retain essentially all of this incident energy. [See for instance, Niedermeyer & Holzl, Phys. Stat. Sol. 11, 651 (1965).] The reflection coefficient $R(E)$ expresses the probability that an electron striking the surface with energy between E and $E+dE$ will be reflected rather than absorbed.

If a beam of electrons having an energy distribution $I(E)$ [such that $I(E)dE$ is the number of electrons crossing a plane normal to the beam current in the unit time with energy between E and $E+dE$ and such that

$$I_o = \int_{E=0}^{\infty} I(E)dE$$

is caused to strike a surface then some of the beam will be reflected and some will be absorbed. The reflected current is given by

$$I_1 = \int_{E=0}^{\infty} R(E)I(E)dE$$

and the energy distribution of the reflected electrons is now $R(E)I(E)$. If the reflected beam is in some way forced to impinge again on the same surface, then the current after this second reflection will be given by

$$I_2 = \int_{E=0}^{\infty} R(E)^2 I(E)dE$$

and the energy distribution of the electrons in this now twice-reflected beam is $R^2(E)I(E)$. Similarly, after n , such reflections the current is

$$I_n = \int_{E=0}^{\infty} R(E)^n I(E)dE$$

and the energy distribution is $R^n(E)I(E)$.

- 10 If the reflection coefficient undergoes maxima and minima as the incident energy (velocity) is increased from zero, then the electron energy (velocity) distribution of a multiply-reflected (diffracted) beam will have sharply defined peaks at energies (velocities) corresponding to each maxima in R overlapped by the initial energy (velocity) distribution. If the positions of these maxima in R are known in advance, then the original energy (velocity) distribution can be shifted by means of accelerating or retarding voltages to give significant overlap with only one of the maxima. In this case, the energy (velocity) distribution of the reflected electrons will be sharply peaked at the one energy (velocity) corresponding to this maximum, and the sharpness of the peak will increase as n , the number of reflections, is increased.
- 20 Even if R has no maxima the energy (velocity) distribution of the reflected electrons will become sharper and sharper at that energy (velocity) corresponding to maximum overlap of R and $I(E)$.

In accordance with the present invention an apparatus is provided so that electrons having the desired initial energy distribution are caused to impinge on one end of the inner surface of a tube (which may have any desired cross sectional configuration—i.e. it is not necessarily a cylindrical tube—it may be two closely spaced plates and thus not even a closed tube). After being reflected by the inside surface of the tube many times, the electrons emerge from the other end of the tube with the narrowed energy distribution described above. They can then be accelerated, decelerated, or focussed as desired.

An object of the present invention is to provide an apparatus to produce low-energy electron beams with narrow energy spreads.

Another object of the present invention is to provide an apparatus for using the energy dependence of the electron reflections to produce an electron beam having a narrower energy distribution than the original source beam.

Yet another object of the present invention is to provide an apparatus to narrow the energy distribution of an electron beam by geometrically forcing the electrons of the beam to undergo successive collisions with a reflecting surface.

Yet another object of the present invention is to provide an apparatus for narrowing the energy distribution of an electron beam by utilizing the energy dependence of the reflection coefficient of a surface for slow electrons in combination with multiple reflection from the reflective surface.

60 The various features of novelty which characterize this invention are pointed out with particularity in the claims annexed to and forming part of this specification. For a better understanding of the invention, however, its advantages and specific objects obtained with its use, reference should be had to the accompanying drawing and descriptive matter in which is illustrated and described a preferred embodiment of the invention.

DESCRIPTION OF THE PREFERRED EMBODIMENT

In the single drawing of the present invention there

is shown electron beam source 1 which may be any conventional electron beam forming apparatus capable of providing low-energy electrons, for example, where $E \leq 3-5$ ev. In electron beam source 1, there is shown voltage source 7 providing voltage by way of transformer 8 for heating filament 9 which thereupon provides a low-energy electron beam emerging from 11. Variable voltage source 10 is utilized to control the intensity of electron beam 2. The output of electron beam source 1 is electron beam 2 which has a broad and the desired initial energy distribution. Tube 3 having inner electron reflecting surface 4 is provided. Tube 3 may have any desired cross-sectional configuration. In place of a cylindrical tube, there may be utilized two closely spaced plates and thus not even a closed tube is necessary. Tube 3 includes input end 5 and output end 6.

Electron beam source 1 is positioned so that the electrons of electron beam 2 are directed into input end 5 of tube 3 so as to impinge at a predetermined angle upon inner surface 4 for reflection therefrom in such manner as to geometrically force the electrons to undergo successive collisions with the reflecting surface without resort to electrostatic or magnetic means. After being reflected by inner surface 4 many times as indicated, the electrons emerge from output end 6 in the form of an electron beam with the desired narrower energy distribution than input electron beam 2 as theoretically described hereinbefore. After emergence from output end 6, the electrons can then be accelerated, decelerated, or focussed, as desired in accordance with any of the conventional uses of an electron beam. It is to be noted that although the structure is not indicated that the apparatus shown in the drawing is attached in the conventional manner to provide the necessary operating conditions for an electron beam such as for example in an operative vacuum and suitable conventional electrodes.

Thus an apparatus has been provided for using the energy dependence of the electron reflection coefficient to produce an electron beam having a narrower energy distribution than the original source beam. This has been accomplished by geometrically forcing the electrons to undergo successive collisions with reflecting surface 4.

In a constructive test of the apparatus of the present invention using literature values of $R(E)$ for polycrystalline Pt [see Niedermeyer & Holzl, Phys. Stat. Sol. 11, 651 (1965)] combined with an initial energy distribution corresponding to normal component of a 3000° K. thermionic energy distribution accelerated by 0.1 volt gave the reduced half-widths and attenuations indicated after 0, 1, 3, 5 and 7 reflections (here $W_{1/2}(0) = 0.175$ ev.) This is a severe test since neither the energy distribution nor this following particular set of reflection data has maximum of the type frequently reported. The half-

width would continue to decrease if n were made larger. Reflection data is as follows:

<i>n</i>	$W_{1/2}(n)/W_{1/2}(0)$	$I(n)/I(0)$
0-----	1.000	1.000
1-----	0.743	0.176
3-----	0.429	0.047
5-----	0.286	0.015
7-----	0.217	0.005

The apparatus of the present invention in effect operates as a non-magnetic reflection type electron velocity filter and provides a novel use of the energy (velocity) dependence of the reflection coefficient of a surface for slow electrons in combination with the use of multiple reflections thereby solving the difficult problem of producing low-energy electron beams with narrow energy (velocity) spreads in much simpler manner.

Although I have shown and described a specific embodiment of my invention, I am fully aware that many modifications thereof are possible. My invention therefore is not to be restricted except insofar as is necessitated by the prior art and the spirit of the appended claims.

What is claimed is:

- 25 1. Apparatus to control and narrow the energy distribution of an electron beam, reflective surfaces having an input end and an output end, said reflective surfaces being at zero potential and free of electric and magnetic fields, an electron beam source providing a low-energy initial electron beam having a wide energy distribution, said electron beam source being positioned to direct the initial electron beam into said input end to impinge at a predetermined angle upon one of said reflective surfaces for reflection therefrom in such manner as to geometrically force the electrons to undergo successive collisions back and forth said reflective surfaces to emit from said output end a resultant beam with a substantially narrower energy distribution than said initial electron beam.
- 30 2. Apparatus to control the energy distribution of an electron beam as described in claim 1 wherein said reflective surfaces is comprised of a tube of preselected length.
- 35 40 3. Apparatus to control the energy distribution of an electron beam as described in claim 1 wherein said reflective surfaces is comprised of a tube of preselected length.
